L. H. GOROWITZ,
FASTENER FOR DOORS AND THE LIKE,
APPLICATION FILED MAR. 26, 1921.

1,413,473.

Patented Apr. 18, 1922.

UNITED STATES PATENT OFFICE.

LOUIS H. GOROWITZ, OF NEW YORK, N. Y.

FASTENER FOR DOORS AND THE LIKE.

1,413,473.

Specification of Letters Patent. Patented Apr. 18, 1922.

Application filed March 26, 1921. Serial No. 455,837.

To all whom it may concern:

Be it known that I, LOUIS H. GOROWITZ, a subject of Russia, and a resident of the city of New York, borough of Manhattan, in **5** the county of New York and State of New York, have invented a new and Improved Fastener for Doors and the like, of which the following is a full, clear, and exact description.

10 This invention relates to improvements in securing devices and more particularly to locks for doors, dormer windows, and other hinged closures, an object of the invention being to provide an improved fastener **15** which secures the door in closed position or in partially open position and which effectually prevents entrance when the fastener is in either of said positions.

A further object is to provide an improved construction and arrangement of fastener which takes the place of and dispenses with the necessity for the ordinary chain in common use and which, when the fastener is released from its door closing **25** position, will automatically assume a position for locking the door in partially open position, so that if any attempt is made to force the door from the outside after it is unlocked, such an attempt will result in **30** failure as the fastener will automatically position itself to secure the door in a partially or limited open position.

A further object is to provide a fastener which can be readily positioned on any door, **35** dormer window, or other hinged closure, which will be neat and attractive in appearance, which can be easily operated by a child as well as an adult, which will be strong and durable in use, and which will **40** most efficiently perform the functions for which it is intended.

With these and other objects in view the invention consists in certain novel features of construction, and combination and arrangements of parts as will be more fully **45** hereinafter described and pointed out in the claims.

In the accompanying drawings—

50 Figure 1 is a view in front elevation illustrating my improved fastener in position to secure the door when the latter is closed.

Figure 2 is a view in transverse section on the line 2—2 of Figure 1.

55 Figure 3 is a view in transverse section partly in elevation showing the fastener in position to permit the door to partially open.

Figure 4 is a view in transverse section on the line 4—4 of Figure 1.

While I shall hereinafter describe my improved fastener in connection with a door, **60** it is obvious that it might be used in connection with a dormer window or any other hinged closure.

1 represents the door and 2 the door frame or jamb, the latter provided with the **65** ordinary flange or bead 3 at its outer portion, against which the door 1 closes so as to prevent the insertion of a tool or other device to manipulate the fastener.

4 represents a plate which is secured to **70** the door 1 by means of screws 5 or other securing devices, and at one end projects beyond the free edge of the door and is bent outwardly and formed with a dove-tailed recess 6, whereby a pair of opposed angular **75** lugs 7 are formed on the end of the plate and positioned at right angles to the plate for a purpose which will hereinafter appear.

A bracket 8 is secured to the frame or **80** jamb 2 by means of screws 9 or other securing devices, and is located in substantial alignment with the plate 4. This bracket 8 is made with a pair of outwardly projecting, perforated lugs 10 receiving one end of a locking lever 11 between them, and a rivet **85** 12 is projected through the lever and through the perforated lugs to provide a pivotal connection for the lever with the bracket.

The end of this lever adjacent the bracket **90** 8 is formed with a bevelled or inclined projection 13, against which the free end of a spring 14 engages. This spring 14 is secured to the bracket 8 by means of a rivet 15 or other securing device, and by reason of its **95** engagement with the lever 11 tends to swing the lever to a position to lock the door in partially open position and also tends to hold the lever in either or both of its other positions, as will be hereinafter pointed out. **100**

This lever 11 is of a width just slightly less than the distance between the adjacent ends of the angular lugs 7 on the plate 4, and from a point slightly removed from the rivet 12 said lever is made with integral laterally projecting flanges 16, which are movable in the dove-tailed recess 6 of said plate 4, and a crosshead or integral pin 17 is formed on the free end of the lever 11 and acts as a stop or abutment against which **105** the plate 4 engages to limit the opening movement of the door. By reason of this

engagement of the plate 4 with the lever 11, it will be noted that the angular lugs 7 prevent said lever from pivotal movement after the door begins to open, as the flanges 16 will engage the lugs if any attempt at pivotal movement is made.

A housing 18 is formed upon or fixed to the plate 4 adjacent one end and in said housing a latch bolt 19 is mounted to move 10 longitudinally. A coiled spring 20 is located in the housing 18 and bears at one end against the rear end 21 of the housing and at its other end against a lug 22 formed on the latch bolt 19. The rear end of this latch 15 bolt projects through an opening 23 in the housing and has a pin 24 fixed thereto, and this pin 24 not only operates to limit the forward movement of the latch bolt, but serves the purpose of a finger hold to per- 20 mit a withdrawal of the latch bolt.

The forward end of the latch bolt 19 is bevelled, as shown at 25, so that when the free end of the lever 11, where the cross-head or pin 17 is provided, is pressed against 25 said latch bolt, it will force the latch bolt rearwardly until the lever 11 is in locking position when said latch bolt will spring forwardly and secure the lever in such position.

30 The bolt 19 is provided on its inner face with a lug 26 adapted to engage a crosspin 27 in the housing 18 to limit the rearward movement of the bolt. A pair of interlocking lugs 28 are formed on plate 4 and behind 35 these lugs 28 the crosshead 17 is held by the latch bolt 19 when the door is closed. These lugs 28 prevent any possibility of longitudinal movement of the lever if any attempt is made to jimmy the door as any pressure 40 of a jimmy between the door and the frame would tend to draw the lever longitudinally, which action would be prevented by the lugs 28.

45 The operation is as follows: Assuming the parts to be in the position shown in Figures 1 and 2, with the latch bolt 19 engaging over the free end of the lever 11, the door will be securely locked in its closed position. When the latch bolt 19 is withdrawn to release the 50 free end of the lever 11, said lever will swing outwardly to the position shown in Figure 3, the spring 14 serving to force the lever to this position.

55 If a person outside of the door attempts to force the door open, this operation will be limited by the length of the lever 11 as the lever will be accommodated in the recess 6 of plate 4 and the projecting end of the 60 plate 4 will engage the crosshead or pin 17 to limit the opening movement of the door. By reason of the bevelled inner end 13 of the lever 11, the spring 14 will normally swing said lever to a position to lock the 65 door when partially open, so that it is not

necessary for any one to guide or position said lever as it will automatically assume its proper position.

In order to permit the door to fully open, it is necessary, while the door is closed, to 70 swing the lever 11 against or parallel with the frame or jamb 2, as indicated by the dot and dash lines in Figure 3, and the lever will be held in this position by the spring 14 until it is again desired for use as a locking means. This complete swinging of the lever to the left is permitted because the flanges 16 terminate short of the pivoted connection 12 and provide ample space between the inner ends of said flanges and the 80 door jamb or frame to allow the lever to swing free of the lugs 7 of plate 4, but this space is only sufficient for this swinging movement when the door is completely closed, so that it is utterly impossible to 85 release the lever from its locking position except when the door is completely closed.

To lock the door in closed position, it is simply necessary to swing the lever 11 against the plate 4, forcing the latch bolt 90 19 rearwardly until the lever is in locking position when said bolt will swing forwardly and effectually lock the door.

While I have illustrated what I believe to 95 be a preferred embodiment of my invention, it is obvious that various slight changes might be made in the general form and arrangement of the parts described without departing from the invention, and hence I do not limit myself to the precise details set forth, but consider myself at liberty to make such changes and alterations as fairly fall within the spirit and scope of the appended claims. 100

I claim:

1. A fastener of the character described, comprising a bracket adapted to be secured to a door frame, a lever pivotally connected to the bracket, a spring engaging the lever and adapted to move and hold the lever in 110 its different positions, a plate adapted to be secured to a door and having a recessed end having interlocking engagement with the lever, a stop on the lever limiting the movement of said plate relative thereto, and a locking device on the plate adapted to hold the lever thereagainst, said locking device comprising a spring pressed latch. 115

2. The combination with a bracket adapted to be secured to a door frame, of a lever pivotally connected to the bracket, a spring engaging the lever and adapted to move and hold the lever in its different positions, said lever having flanges thereon and having a stop at its free end, a plate adapted to be secured to a door, said plate having one end projecting beyond the free end of the door and having a dove-tailed recess therein receiving the lever and by reason of its engagement with the flanges of the lever. 120 125 130

5 preventing pivotal movement of the lever when the door is partially open, and said plate adapted to engage the stop on the lever to limit the opening movement of the door.

10 3. The combination with a bracket adapted to be secured to a door frame, of a lever pivotally connected to the bracket, a spring engaging the lever and adapted to move and hold the lever in its different positions, said lever having flanges thereon and having a stop at its free end, a plate adapted to be secured to a door, said plate having one end projecting beyond the free end of the door 15 and having a dove-tailed recess therein receiving the lever and by reason of its engagement with the flanges of the lever preventing pivotal movement of the lever when the door is partially open, said plate adapted 20 to engage the stop on the lever to limit the opening movement of the door, a housing on the plate, and a spring pressed latch bolt in said housing adapted to engage the free end of the lever and secure the door in closed 25 position.

4. The combination with a door, and a

door frame, of a bracket secured to the door frame having lugs thereon, a lever pivotally supported between the lugs and the bracket and having a bevelled inner end, a 30 spring on the bracket engaging the bevelled end of the lever and adapted to move and hold said lever in its different positions, said lever adapted to be positioned flat against the door at an angle to the door and substantially parallel to the frame, a stop on the free end of said lever, flanges on the lever extending from its outer end to a point removed from its inner end, a plate secured to the door and having one end projecting 35 beyond the free end of the door and positioned at an angle to the door, said projecting end of the plate having a dove-tailed recess therein movable on the flanged portion of the lever and adapted to engage the stop 40 at the free end of the lever to limit the opening movement of the door, and a latch bolt on the plate adapted to engage the free end of the lever and secure the door in closed 45 position.

LOUIS H. GOROWITZ.
